Primary Examiner — Jack Reickel*Assistant Examiner* — Salamah Jordan(74) *Attorney, Agent, or Firm* — McAndrews Held & Malloy, Ltd.(57) **CLAIM**

The ornamental design for a gaming machine, as shown and described.

DESCRIPTION

FIG. 1 is a front perspective view of a gaming machine showing my new design;

FIG. 2 is a front elevation view thereof;

FIG. 3 is a rear elevation view thereof;

FIG. 4 is a right elevation view thereof;

FIG. 5 is a left elevation view thereof; and,

FIG. 6 is a top plan view thereof.

The dashed broken lines in the drawings illustrate portions of the gaming machine that form no part of the claimed design.

1 Claim, 4 Drawing Sheets(56)
